COMBINED WINDOW SHADE AND AWNING

Filed Aug. 30, 1921

Patented Dec. 4, 1923.

UNITED STATES PATENT OFFICE.

EILER POULSEN, OF NEW YORK, N. Y.

COMBINED WINDOW SHADE AND AWNING.

Application filed August 30, 1921. Serial No. 496,861.

To all whom it may concern:

Be it known that I, EILER POULSEN, a citizen of Denmark, and residing at New York, in the county of New York and State of New York, have invented certain new and useful Improvements in Combined Window Shades and Awnings, of which the following is a specification, such as will enable those skilled in the art to which it appertains to make and use the same.

This invention relates to window shades and awnings, and the object thereof is to provide a window shade construction whereby the shade may be used not only for the usual purposes but for an awning; and with this and other objects in view the invention consists in the construction, combination and arrangement of parts hereinafter described and claimed, and whereby my invention is reduced to practical and operative form.

The invention is fully disclosed in the following specification, of which the accompanying drawing forms a part, in which the separate parts of my improvement are designated by suitable reference characters in each of the views, and in which:

Fig. 1 is a vertical sectional view of an ordinary window construction provided with my improvement and showing a shade used as an awning;

Fig. 2 a section on the line 2—2 of Fig. 1; and,

Fig. 3 a view similar to Fig. 1 but showing the different arrangements of the parts.

In the drawing forming part of this specification, I have shown a window frame comprising top and bottom members *a* and *a*² and side members *a*³, and mounted in said frame are the usual top and bottom sashes *b* and *b*², and it will be understood that these sashes may be counter-balanced in the usual manner and raised or lowered into any desired position.

In the practice of my invention I provide an ordinary shade roller *c* on which the usual shade *c*² is wound, and said shade is narrower than the inner transverse dimensions of the window frame to permit said shade to be swung inwardly and outwardly, or used on the inner side of said frame or on the outer side thereof as may be desired.

The shade *c*² is provided at the free end thereof with a transverse rod *c*³, the ends of which are provided with hooks *c*⁴, and the sides of the window frame are provided

centrally, or approximately centrally with eyes *d* below which are similar eye or hook bolts *d*² and *d*³. I also employ awning arms *e* which are telescopic in form and construction and the lengths of which may be adjusted by means of set screws *e*² which are passed through the outer end portions of the outer members of said arms and bear on the inner end portions of the inner members of said arms.

The awning arms *e* are provided at their inner ends with hooks *e*³ adapted to engage the eye bolts *d*, *d*² and *d*³ and at their outer ends said arms are provided with eye devices *e*⁴ adapted to engage the hooks *c*⁴ at the free end of the shade.

The operation or use of my invention will be readily understood from the foregoing description when taken in connection with the accompanying drawing and the following statement. The shade *c*² may be supported by or suspended from the roller *c* as shown in dotted lines in Fig. 1 in which position it will serve as an ordinary shade, and when it is desired to use said shade as an awning as shown in Figs. 1 and 2, the upper sash *b* is lowered and the shade passed outwardly thereover through the space above said sash as shown at *f* and at this time the awning arms *e* are brought into use, and one end thereof connected with the eye bolts or other devices *d* while the other ends thereof are connected with the opposite ends of the rod *c*³ in the free end of the shade as shown in full lines in Figs. 1 and 2.

The awning arms *e* may be adjusted to any desired length and the shade moved inwardly toward, or outwardly from, the window frame as may be desired and said awning arms may be adjusted to such length that the free ends thereof will swing to or into the top of the window frame, or downwardly and inwardly to the bottom of the window frame, and said awning arms may be connected with the eye bolts or other devices *d*² and *d*³ as will be readily understood, and in this way the position and operation of the shade as an awning may be adjusted and regulated to any desired extent.

With the apparatus shown as indicated in Figs. 1 and 2 there would, of course, be some light admitted at the opposite sides, or at one particular side, according to the position of the sun and in order to remedy this defect to an extent, one of the awning arms

e, in any position of said arms, may be detached, and the free end of the shade or the rod *c*³ therein may be used as indicated in Fig. 3, and in which position the free end of 5 the shade is connected with one of the parts *d*—*d*² or *d*³, and the other end connected with the opposite or other awning arm, and this, of course, will prevent the sunlight from entering at one side of the awning.

10 I also provide a stay cord *g* which is adapted to be connected with the free end of the window shade *c*² centrally thereof as shown at *g*² and which is also adapted to be connected with the central bottom portion of the window sill as shown at *g*³, and this will hold the shade when used as an awning in proper position at all times and prevent its being swung about, or moved upwardly and downwardly by the 20 wind.

By means of the construction herein described it will be seen that I provide a simple and effective means whereby an ordinary window shade may be used at any time for the purpose for which it is intended and also used when so desired as a simple and efficient window awning, and although I have shown one form of construction for carrying my invention into effect or for 25 reducing it to practical form, it must be understood that the said invention is not limited to the details of construction herein shown and described, and changes therein and modifications thereof may be made 30 within the scope of the appended claims, without departing from the spirit of my invention or sacrificing its advantages.

Having fully described my invention, what I claim as new and desire to secure 40 by Letters Patent, is:—

1. A combination window shade and awning for windows comprising a shade roller on which is mounted a shade, said shade being adapted to be passed outwardly 45 through a window opening over the top of the window and provided at its free edge portion with a transverse rod, attaching devices on the ends of said rod, attaching devices spaced vertically on the outer faces 50 of the side members of the window frame, and arms adapted to be detachably mounted in connection with the attaching devices on said side members and on the ends of said

shade rod, and the attaching device on said shade rod being adapted to be coupled 55 with the spaced attaching devices of the window frame.

2. A combination window shade and awning for windows comprising a shade roller on which is mounted a shade, said shade being adapted to be passed outwardly 60 through a window opening over the top of the window, and provided at its free edge portion with a transverse rod, attaching devices on the ends of said rod, attaching devices spaced vertically on the outer faces of the side members of the window frame, arms adapted to be detachably mounted in connection with the attaching devices on said side members and on the ends of said shade 65 rod, the attaching device at each end of the rod being adapted for direct connection with any one of the attaching devices on the corresponding side of the window frame.

3. A combination window shade and awning for windows comprising a shade roller on which is mounted a shade, said shade being adapted to be passed outwardly 70 through a window opening over the top of the window, and provided at its free edge portion with a transverse rod, attaching devices on the ends of said rod, attaching devices spaced vertically on the outer faces of the side members of the window frame, arms adapted to be detachably mounted in connection with the attaching devices on said side members and on the ends of said shade 75 rod, the attaching device at each end of the rod being adapted for direct connection with any one of the attaching devices on the corresponding side of the window frame, and one of said arms being detached from one end of the shade rod in coupling the attaching device at said end of the rod with one of the attaching devices on the window 80 frame to support said rod at an angular position to said window frame.

In testimony that I claim the foregoing as my invention I have signed my name in presence of the subscribing witnesses this 27th day of August, 1921.

EILER POULSEN.
